UNITED STATES PATENT OFFICE.

EDWARD McCAMMON, OF ALBANY, NEW YORK.

PIANO-FORTE.

SPECIFICATION forming part of Letters Patent No. 258,455, dated May 23, 1882.

Application filed December 27, 1881. (No model.)

To all whom it may concern:

Be it known that I, EDWARD McCAMMON, of the city and county of Albany, and State of New York, have invented certain new and useful Improvements in Upright Piano-Fortes, of which the following is a specification.

My invention relates to improvements in the casings of upright pianos; and the object of my invention is to provide a detachable ornamental casing for the instrument, so as to render the latter lighter to handle, to avoid the danger of scratching or otherwise disfiguring the ornamental external casing while the instrument is being moved, and to reduce the size of the instrument so as to allow it to pass through a narrow space. This object I attain by means of the construction illustrated in the accompanying drawings, which form part of this specification, and in which—

20 Figure 1 is an end elevation of an upright piano provided with my detachable casing; Fig. 2, the same with one of its end pieces, fronts, and action removed, and the top, key-board bottom, and pedal-rail shown in section; Fig. 3, an end elevation of the inside or body frame stripped of all its detachable parts; Fig. 4, a plan view with the top, front, and action removed; and Fig. 5, an inverted plan view, showing one of the caster-blocks broken off.

In the accompanying drawings, A designates the inside or body frame of the instrument, which frame, when provided with the usual iron plate, strings, and sounding-board, 35 is known to the trade as an "upright back, bellied;" B, a detachable top, secured to the frame A by means of screws, and provided with the usual hinged piece or flap, b; C, detachable end pieces, provided with cheek-pieces c and caster-blocks c', that are permanently secured to said end pieces. The end pieces, C, are secured to the frame A by means of the screws c², which are covered by the top B and the back fastenings, c³, which consist 40 of the ordinary butt-hinge provided with removable pins c⁴, or any equivalent separable fastening device. The said end pieces, C, are provided on their inner sides with recesses adapted to fit snugly upon the dowel-pins a, 45 secured in the frame A, and by this means the end pieces are always restored to and held in their exact positions in respect to the frame

A. D, the pedal-rail, secured at both ends to the caster-blocks c' by means of the dovetails d, which aid in retaining the lower parts of 55 the end pieces, C, snugly in place against the frame A; E, the detachable key-board bottom, which is secured to the under edges of the cheek-pieces c by means of the screws e.

The action, key-board, and fronts of the instrument are made removable, in the usual manner of constructing upright pianos, and for the purposes of this description it must be understood that the parts last named have been removed from the constructions shown in 65 the drawings.

The *modus operandi* for removing the external casing from the piano is as follows: The instrument is tilted backward to permit the removal of the pedal-rail D and key-board 70 bottom E. Then, after the top B has been removed, the screws c² are taken out and the pins c⁴ are removed from the back fastenings, c³, after which the end pieces, C, with their attached cheek-pieces c and caster-blocks c', can 75 be drawn off from the dowel-pins, so as to leave the frame A in the condition shown in Fig. 3, stripped of all external ornamentation that is liable to be injured by being scratched or bruised. At the same time the instrument is 80 relieved of so much of its weight that it can be handled and carried with comparative ease, while the reduction in its size permits the instrument to pass readily through a very narrow opening or passage-way.

I claim as my invention—

1. In an upright piano, the combination, with a body-frame, A, containing the usual iron plate, strings, and sounding-board, of an outer ornamental casing separable from the 90 frame A, substantially as described, and for the purpose set forth.

2. The combination, with the body-frame A for containing the plate, strings, and sounding-board of an upright piano, of an ornamental casing consisting of the end pieces, C, 95 pedal-rail D, and key-board bottom E, separable from the frame A, essentially as and for the purpose specified.

EDWARD McCAMMON.
